a corporation of New Jersey

Application March 28, 1939, Serial No. 264,570

3 Claims. (Cl. 255—45)

This invention relates to rock drilling mechanism, and more particularly to a cushioning device for rock drilling mechanism of the type that is actuated mechanically to and from the work.

5 In a more specific sense, the invention is intended for use in connection with rock drills equipped with a motor for effecting feeding movement. In the operation of apparatus of this character, only a comparatively small portion of 10 the operator's time is required for manipulating the feeding mechanism. Normally, it is merely necessary to set the feeding motor in operation at the beginning of a cut and to again reverse the motor at the end of the run for retracting the 15 rock drill to its initial starting position. In the interim the operator is free to perform such other duties as may arise in connection with the work.

Under these circumstances it may happen that the operator is occupied with other matters at the 20 time the rock drill reaches its rearmost position and that the motor is, therefore, not cut off from the power supply before the rock drill engages relatively fixed portions of the drilling mechanism. In such case the rock drill is often forced 25 into such tight locking engagement with other portions of the drilling organization that it is impossible to again start the motor without practically disassembling it to free the rotary elements of the feeding mechanism.

30 It is accordingly an object of the invention to prevent the feeding motor from forcing the rock drill into tight binding engagement with other portions of the drilling mechanism.

Other objects will be in part obvious and in part 35 pointed out hereinafter.

In the drawing accompanying this specification and in which similar reference numerals refer to similar parts,

Figure 1 is a longitudinal side elevation of a 40 drilling mechanism equipped with a cushioning device constructed in accordance with the practice of the invention,

Figure 2 is an enlarged longitudinal view, in section, showing the cushioning device interposed 45 between the rock drill and the feeding motor, and

Figures 3 and 4 are perspective views of details.

Referring more particularly to the drawing, the drilling mechanism embodying the invention 50 and designated by 20, comprises a rock drill 21, a support member or shell 22 and a rotary feeding motor 23 attached to the end of the shell by means of rods 24 for actuating the rock drill 21 longitudinally of the shell.

55 The rock drill 21 may be provided with the usual

hammer piston (not shown) for actuating a drill steel 25 into the work, and on the sides of the rock drill are the usual ribs 26 which extend into guideways 27 in the shell for connecting the rock drill and the shell slidably together. 5

Near the rearward end of the rock drill is a depending lug 28 having a bore 29 to receive a feed nut 30 clamped in position by a nut 31 threaded on a rearwardly projecting end of the feed nut and seating against the adjacent end 10 of the lug 28. The feed nut 30 is threaded to accommodate a feed screw 32 which may be suitably supported at its front end by the shell 22 and is in interlocking engagement at its rearward end with the motor 23 whereby the feed screw is 15 rotated.

The motor 23 may be of any suitable pressure fluid actuated type and on its rotor is a gear 33 which meshes with planet pinions 34 mounted upon a spider 35 in the end of the motor casing 20 36. The spider 35 carries a skirt 37 which is rotatable in the end of the casing 36 and has a tapered bore 38 to receive a correspondingly tapered shank 39 of the feed screw 32. The shank 39 is locked to the skirt 37 by a key 40, 25 and on the end of the shank is a threaded extension 41 to accommodate a nut 42 that seats upon a shoulder 43 on the spider 35 for securing the spider to the shank 39. Preferably, a bushing 44 is disposed in the end of the casing 36 to provide 30 a renewable bearing surface for the sleeve 37 and on the outer end of the bushing 44 is a flange 45 which overlies the end of the casing 36.

The feed screw 32 is of the conventional type having a collar 46 which abuts a thrust plate 47 35 encircling the shank 39 and seating against the flange 45. Thus, the collar 46 serves to prevent the imposition of severe end thrust upon the rotary elements of the motor. The thread of the feed screw 32 comes sufficiently close to the collar 46 to make it possible for the feed nut to be brought into engagement with the collar. In prior structures of this character this arrangement often brought about a situation in which the feed nut was jammed so tightly against the 40 collar 46 that it was impossible for the motor to rotate the feed screw for forward feeding movement of the rock drill. Hence, it became necessary to disconnect the motor from the feed screw and then rotate the feed screw by manual force 45 for freeing the collar 46 from the feed nut.

In order to avoid this troublesome occurrence the feed screw is provided with a cushioning device interposed between the rock drill and the motor. The cushioning device comprises an 55

abutment member 48 consisting of two half sections 49 which are disposed slidably about the feed screw to seat against the rearmost end of its thread, and on the opposite end of the member 5 48 is a reduced stem 50 to receive a ring 51 for retaining the sections 49 on the feed screw.

The ring 51, in turn, has a stem 52 of reduced diameter to receive an end of a spring 53 which abuts against a shoulder 54 on the ring. The 10 other end of the spring encircles the collar 46 and seats against the plate 47. The spring is thus held against vibratory movement laterally of the feed screw and, in practice, is also placed initially under compression so that it will constantly tend to press the member 48 against the 15 end of the thread of the feed screw.

During the operation of the drilling mechanism and when the rock drill approaches its rearmost limiting position the feed nut will engage the 20 member 48. Continued rearward movement of the rock drill will cause the spring 53 to be compressed and, in the event that the operator fails to cut-off the power supply to the motor, will cause the motor to stall. The rock drill, however, 25 will abut only the member 48 which, although arranged on the feed screw, cannot effect a locking engagement between the rock drill and the feed screw and the rock drill is, therefore, free at all times to proceed in a forwardly direction.

30 I claim:

1. In a cushioning device for a rock drilling mechanism, the combination of a rock drill and a feed screw in threaded engagement therewith,

a motor for rotating the feed screw, a spring on the feed screw to receive the thrust of the rock drill and thereby prevent the motor from forcing the rock drill into binding engagement with other portions of the drilling mechanism, and means for preventing vibratory movement of the spring with respect to the feed screw. 5

2. In a cushioning device for a rock drilling mechanism, the combination of a rock drill and a feed screw in threaded engagement therewith, 10 a motor for rotating the feed screw, an abutment for the rock drill slidable on the feed screw, a spring acting against the abutment to resist rearward movement of the rock drill relatively to the feed screw and thereby prevent the motor from 15 forcing the rock drill into binding engagement with other portions of the drilling mechanism, and means for preventing vibratory movement of the spring with respect to the feed screw.

3. In a cushioning device for a rock drilling 20 mechanism, the combination of a rock drill and a feed screw in threaded engagement therewith, a motor for rotating the feed screw, an abutment for the rock drill slidable on the feed screw adjacent the motor, a spring interposed 25 between the abutment and the motor to resist rearward movement of the rock drill with respect to the feed screw and thereby prevent the motor from forcing the rock drill into binding engagement with other portions of the drilling mech- 30 anism, and means for preventing vibratory movement of the spring with respect to the feed screw.

ARTHUR F. DICKER, SR.
